TRAILER

Lee O. Dykes, Jr., and Lillian Hope Dykes,
Milwaukee, Oreg.

Application December 14, 1948, Serial No. 150,148

Term of patent 14 years

(Cl. D14—3)

To all whom it may concern:

Be it known that we, Lee O. Dykes, Jr., and Lillian Hope Dykes, residing in the county of Clackamas and State of Oregon, have invented a new, original, and ornamental Design for a Trailer, of which the following is a specification, reference being had to the accompanying drawings, forming part thereof.

It is to be understood that both sides of the trailer are identical but, of course, reversed.

The characteristic features of our design reside in the portions shown in full lines in the drawing.

We claim:

The ornamental design for a trailer, as shown and described.

LEE O. DYKES, JR.,
LILLIAN HOPE DYKES.
